M. MCCOY.

ADJUSTABLE RATCHET WRENCH.
APPLICATION FILED DEC. 27, 1910.

1,000,277.

Patented Aug. 8, 1911.

UNITED STATES PATENT OFFICE.

MARTIN McCOY, OF PLEASANT, KENTUCKY.

ADJUSTABLE RATCHET-WRENCH.

1,000,277.

Specification of Letters Patent. Patented Aug. 8, 1911.

Application filed December 27, 1910. Serial No. 599,326.

To all whom it may concern:

Be it known that I, MARTIN McCoy, a citizen of the United States, residing at Pleasant, in the county of Martin and State 5 of Kentucky, have invented new and useful Improvements in Adjustable Ratchet-Wrenches, of which the following is a specification.

This invention relates to improvements 10 in wrenches.

The object of the present invention is to improve the construction of ratchet wrenches and to provide a simple, inexpensive and efficient one adapted to be readily adjusted 15 to suit the diameter of a pipe, rod or nut and firmly grip the same.

The invention consists in the construction 20 and novel combination and arrangement of parts, as hereinafter fully described illustrated in the accompanying drawings, and 25 pointed out in the claim hereto appended.

In the drawings, Figure 1 is a perspective 30 view of a ratchet wrench constructed in accordance with the present invention. Fig. 2 is a central longitudinal sectional view. Fig. 3 is a longitudinal sectional view upon the line 3—3 of Fig. 2. Fig. 4 is a transverse sectional view. Fig. 5 is a perspective 35 view of the adjusting wheel. Fig. 6 is a similar view of one of the adjusting jaws. Fig. 7 is a perspective view of one of the removable adjusting wheel sustaining members.

In the accompanying drawing the number 40 1 designates a shank or stock carrying a head 2 and constituting a handle, and the said head 2, which is preferably in the form of a ring, as shown, to provide a circular opening is formed with longitudinally arranged oppositely disposed recesses or 45 pockets 3 and 4, the same also communicating with the sides of the shank or handle 1. Positioned within the pockets 3 and 4 are spring-pressed dogs 5 and 6. The recesses of the head as well as the outer faces of the 50 pockets communicate with the exterior of the outer faces of both the head and the handle and the sides of the handle adjacent the extremities of the spring-pressed dogs 55 are recessed for the reception of pivoted operating wheels designated by the numerals 8 and 9. The said operating wheels have their peripheries milled and their inner faces cam-shaped as at 10 so as to provide means whereby upon the rotation of the 60 wheels the said cams bearing against the

inner ends of the dogs will cause their faces positioned within the recesses of the circular head to project within the opening provided by the head or to be retracted 60 from the said opening as desired.

The numeral 11 designates a flanged ratchet wheel which is adapted to be positioned within the circular head of the wrench and to have its teeth 12 engaged by 65 the diametrically oppositely arranged dogs 5 and 6, depending, of course, upon which way the ratchet wheel is to be rotated or when the ratchet wheel it to be held against rotation. The ratchet wheel 11 is centrally 70 provided with a rectangular depression 13 which provides a substantially horizontal wall and right angular walls 15. The horizontal wall or face 14 is centrally provided with a longitudinally extending opening 16. 75 This opening 16 is of a rectangular formation and is of a lesser width and length than the wall 14. The said opening 16 is adapted for the reception of the downturned reduced portions or ends 17 provided upon the adjustable jaws 18. These jaws 18 may have 80 their engaging faces 19 serrated if desired, so that the said jaws will readily engage with a pipe or rod. The body portion of each of the sliding jaws 18 is of a width and 85 thickness equaling the width and depth of the depression 13. The horizontal wall 14 provided by the depression 13 is adapted to lie in a parallel plane with the face of the stock or shank opposite to that engaged by 90 the offset of the ratchet wheel, and the upper faces of the body of the movable jaws are each provided with spaced teeth 20.

The numeral 21 designates the adjusting wheel for the jaws. This wheel 21 is centrally provided with an annular opening 95 and has its under face formed with a spiral flange 22, the same being adapted to engage with the teeth 20 formed upon the movable jaws. The periphery of the adjusting wheel 100 21 is milled as at 23, so that the said wheel may be freely rotated so as to have its spiral 22 force the jaws toward or away from the center of the head to grip or release an article.

In order to removably secure the parts in proper position upon the head 2, the ratchet wheel 12 is provided upon its walls formed by the longitudinal cut-away portion with oppositely arranged dove-tailed 110 slots 25 and 26. These slots preferably have their inner faces rounded so that the said

wall projects within the walls 15 of the ring. These rounded walls are also inclined from the top of the ratchet wheel to the bottom thereof and are adapted for the reception 5 of the dove-tailed ends 27 and 28 of the adjusting wheel securing members 29 and 30. Both of these elements 29 and 30 have their inner faces rounded and beveled or inclined to agree with the inclined inner faces of the 10 V-shaped or dove-tailed cut-away portions provided by the ratchet wheel. The inner faces 31 of each of the members 29 and 30 are each formed adjacent their upper portions with a reduced straightened face, the 15 side walls of which terminate a slight distance beyond the walls 15 of the said ratchet wheel, while the dove-tailed portions of each of the retaining members are arranged in a parallel line with the walls provided by 20 the longitudinal opening of the ratchet wheel to provide for the free sliding of the depending portion 17 of the sliding jaws. These dove-tailed portions are each provided with suitable openings, as are the 25 dove-tailed recesses, the latter being threaded and these openings are adapted for the reception of suitable removable securing elements designated by the numeral 32, the heads of which being received in counter- 30 sinks formed in the outer faces of the wheel retaining members. The upper and outer faces of the retaining members are rounded and are further provided with flanges 33, the latter being adapted to engage the wall 35 and upper face of the adjusting wheel adjacent the circular opening thereof.

The movable jaws 18 have their elongated bodies at all times overlying the circular head and the shank of the device, so it will 40 be noted that when the retaining members engage the adjusting wheel, all of the component parts of the wrench will be effectively sustained in position upon the head of the wrench. The sides or edges of the 45 movable jaws 18 adjacent their depending portions 17 are reduced a suitable distance so as to provide shoulders 34 which are positioned a distance away from the engaging faces 19 equaling one-half of the width of 50 the retaining members and whereby the said jaws, when in their closed position are retained centrally of the said retaining mem-

bers so that the said jaws when opened will each slide away from each other at an equal rate of speed.

From the above description, taken in connection with the accompanying drawings, it will be noted that I have provided an extremely simple and effective device for the purpose intended, and while I have illustrated and described the preferred embodiment of the improvement, as it now appears to me, minor details of construction, within the scope of the following claim may be resorted to if desired.

Having thus fully described the invention, what I claim as new is:—

In a wrench of the class set forth, the combination with a flanged ratchet wheel and spring-pressed dogs for engaging the ratchet wheel, said ratchet wheel being provided with a longitudinally extending depressed portion and a rectangular opening communicating with the said depressed portion, the longitudinal walls provided by the opening being formed with dove-tailed slots having their rear walls curved and inclined from the top of the wheel to the bottom thereof, removable members having dove-tailed lower portions for the dove-tailed slots, the inner faces of the said members being reduced above the wall provided by the depression and being longitudinally straight, the edges of the straightened portion having their opposite ends cut away adjacent the dove-tailed portions, the outer face of each of the members being rounded and their upper extremities formed with an offset, sliding jaw members within the opening, said members each being provided with shoulders adapted to engage the walls provided by the cut away portions of the removable members, and a jaw adjusting wheel provided with a central opening adapted to be engaged by the rounded portions of the removable members and to have its upper face contacted by the offsets thereof.

In testimony whereof I affix my signature in presence of two witnesses.

MARTIN MCCOY.
